NOVELTY PADDLE

Eleanor B. Krost, Henrico County, Va.
(308 El Dorado Drive, Richmond, Va. 23229)

Filed Mar. 28, 1967, Ser. No. 6,407

Term of patent 14 years

(Cl. D34—5)

FIG. 1.

FIG. 2.

FIG. 3.

The broken lines in FIGS. 1 and 2 indicate conventional legible matter.

I claim:

The ornamental design for a novelty paddle, as shown and described.
